J. MATTSON

SILO

Filed Aug. 25, 1921

INVENTOR
J. Matteson

BY *Munn & Leo*
ATTORNEYS

UNITED STATES PATENT OFFICE.

JULIUS MATTSON, OF CHICAGO, ILLINOIS.

SILO.

Application filed August 25, 1921. Serial No. 495,160.

To all whom it may concern:

Be it known that I, JULIUS MATTSON, a citizen of the United States, and a resident of Chicago, in the county of Cook and State 5 of Illinois, have invented a new and useful Improvement in Silos, of which the following is a full, clear, and exact description.

My invention relates to improvements in 10 silos, and it consists in the combinations, constructions and arrangements herein described and claimed:

An object of my invention is to provide 15 an improvement over the silo disclosed in my prior application for patent, Serial No. 483,849, filed July 11, 1921, in which I disclosed a silo having a closure supported for movement vertically, said improvement consisting in the provision of a flexible 20 closure adapted to conformably fit within the silo casing at all times and being supported for movement vertically.

A further object of my invention is to 25 provide a novel means for balancing the weight of the closure to insure ease of operation.

A further object of my invention is to 30 provide a device of the character described that is simple in construction and can be produced with the materials ordinarily available.

Other objects and advantages will appear 35 in the following specification, and the novel features of the invention will be particularly pointed out in the appended claims.

My invention is illustrated in the accompanying drawings, forming part of this application, in which—

Fig. 1 is a vertical section through a 40 silo embodying the invention, portions thereof being broken away and other portions being shown in section,

Fig. 2 is a plan view of the device,

Fig. 3 is a plan view of a closure embodied 45 in the device, and

Fig. 4 is a front elevation of a fragmentary portion of the device.

Referring now to the drawings, 1 denotes 50 a vertically disposed cylindrical silo casing resting upon a base 2 and provided with usual doors 3 through which the contents of the silo may be removed at will. In the present instance, the closure embodied in the device comprises a case formed of an upper cover 4 and a lower cover 5 connected by a cylindrical body 6. The upper cover

4 and the lower cover 5 are precisely identical in essential respects and each has a diameter approximately equal to the inner diameter of the silo casing 1. The upper 60 cover 4, the lower cover 5, and the body 6 of the closure casing may be made of wire netting of fine mesh, a porous fabric, or like material. A suitable packing 7 is arranged within the closure casing to overlie the lower cover 5 at all points, except at the center thereof and to form a layer located contiguous to the inner wall of the body 6, as clearly shown in Fig. 1. Any suitable material that is a poor conductor 70 of heat and is capable of being packed to provide an impervious layer may be used for the packing 7. I have found that partly seasoned straw is suitable for the purpose. Other material that will provide a 75 layer 8 through which air may permeate is then superposed on the lower layer 7. An upper impervious layer 7^a of the packing employed in forming the lower layer 7 is arranged between the intermediate porous 80 layer 8 and the upper cover 4.

The closure is suspended from a frame 9 comprising inclined bars 10 supported on the silo casing 1 at the upper end of the latter and converging together at their upper ends. The silo casing is equipped with a strengthening band 11 adjacent to its upper end. A connector is provided for each of the inclined frame bars 10 and embodies a hook portion 46 engaging with the band 90 and a shank portion 47 projected between the band 11 and the silo casing and secured by bolts 48 or the like to the bar 10. It will thus be apparent that the supporting frame 95 is secured in place on the silo without any necessity for perforating the silo casing to receive attaching means. A cable 12 is attached at its lower end to a tie member 13 that extends through the center of the closure and is attached to both the upper cover 100 4 and the lower cover 5. In order to distribute the strain incident to the raising of the closure and to permit the manipulation of the closure within the casing without changing the position of its axis relatively to the axis of the casing, I provide a plurality of radially extending tie wires 14. Each of the tie wires 14 is connected at its upper end with the cable 12 and is arranged to extend vertically through the closure at a point adjacent to the outer edge of the latter, being attached to both the outer cover 4 and

the lower cover 5. In addition, vertical tie wires of equal length, such as indicated at 15 are provided for each of the inclined tie wires 14 and are attached to the latter at their upper 5 ends and to the lower cover 5 at their lower ends in any suitable manner, such as knots in the wires 15 below the cover 4 and the cover 5. Still other tie wires 17 and 18 are attached intermediately to each of the inclined tie wires 14, are arranged with their ends extended through the closure and are attached to both the upper cover 4 and the lower cover 5. It will thus be apparent that when a pull is exerted on the cable 12, which 10 is passed through a pulley 19 carried by the supporting frame 9, that the flexible closure will be raised and at the same time will constantly conformably fit the casing 1 to prevent the passage of air or other gases between the outer wall of the closure and the casing. The cable 12 is passed through a guide pulley 20 carried by a frame, indicated generally at 21, that is attached to the frame 9, and is conducted around a guide roller 22 15 to a hoisting drum 23. The guide roller 22 is positioned at the lower end of the casing 1 and is supported by parallel vertical rails 24-24. The rails 24-24 extend above the upper end of the casing 1 and are connected 20 by a cross member 25 with the frame 21. The hoisting drum 23 is mounted on a shaft 26 journaled in inclined vertical bars 27-27 that are connected at their upper ends by a cross member 28 and connected with the 25 bars 24-24 by parallel horizontally disposed members 29-29. The shaft 26 projects laterally of one of the bars 27 and is provided with a stirrup 30 at its end through which a crank arm 31 is projected. A wedge 32 is driven between the stirrup 30 and the 30 crank arm 31 and secures the latter in adjusted position with respect to the axis of the shaft 26, whereby a greater or less leverage may be had, as desired. A band 33 is placed 35 on the drum 23 and is indented around its periphery as at 34 to engage with a pawl 35 pivotally attached to one of the members 27, whereby the drum 26 is held against rotation in one direction. A plurality of pins 36 extends radially from the drum 23 adjacent to its ends and serve as rim members to prevent the coils of the cable 12 from disengaging the drum 23.

A series of vertically aligned racks 45, 37, 55 38 and 39 are attached to the track members 24-24. Each of these racks has the form of a rectangular frame, as best seen in Fig. 2. A weight 40 rests upon the rack 39. A weight 41 rests upon the rack 38 and a weight 42 is supported on the rack 37. These weights are provided with vertically aligned openings through which the cable 12 extends. A weight 43 is attached to the cable 12 and is normally positioned below 60 the rack 37. It is important to note that

while each weight can be moved through the racks positioned above the rack on which it normally rests, it cannot be moved downwardly through lower racks. Each of the weights is provided with opposite notches 70 44-44 adapted to engage with adjacent faces of the track members 24-24.

From the foregoing description of the various parts of the device, the operation thereof may be readily understood. On account 75 of the balanced construction, the closure may be moved readily when the hoisting drum 26 is manipulated. As the closure is lowered in the casing, the lower weight 43 will be raised from its rack or rest 45 through the racks positioned thereabove. It will be manifest that all weights will be suspended on the cable above the upper rack 39 when the closure has been lowered to the bottom of the casing 1 and that each weight will 80 rest on its rack when the closure has been raised to the upper end of the casing 1. Since the upper layer 7^a of the closure is 85 impervious, the heated air and gases passing upwardly and accumulating at the center of the silo are prevented from escaping while permitted to penetrate the pervious intermediate layer 8 at the center thereof and to radiate toward the outer edge of the closure. The temperature within the silo will thus be 90 uniformly maintained under varying weather conditions and the ensilage will be kept in sound condition.

I claim:

1. In a silo having a vertically disposed 100 casing, a closure movably disposed in said casing and comprising a case of porous flexible material, a filling of heat impervious material disposed in said case, and a cover of wire netting over said case.

2. In a silo having a vertically disposed 105 casing, a closure movably disposed in said casing and comprising a case of porous flexible material, a filling of heat impervious material in said case, and flexible supporting 110 members attached to said closure and arranged for connection with a cable or the like to support said closure.

3. In a silo, a vertically disposed casing, a closure comprising a case made of a porous 115 flexible material and consisting of an upper cover and a lower cover connected at their edges by a body portion adapted to conformably fit within the silo casing, a layer of dense impervious packing disposed on 120 the lower cover and arranged contiguous to the body portion, said packing being disposed to provide a layer having a central opening, an intermediate layer of pervious packing superposed on the first named layer 125 and filling the central opening in the first named layer, and an upper layer of dense impervious packing superposed on the intermediate layer and filling the space between the latter and the upper cover, and 130

means for movably supporting the closure within the silo casing.

4. In a silo, a vertically disposed casing, a closure comprising a case made of a porous flexible material and consisting of upper and lower covers connected at their edges by a body portion adapted to conformably fit within the silo casing, a layer of dense impervious packing disposed on the lower cover and arranged contiguous to the body portion, said packing being disposed to provide a layer having a central opening, a layer of pervious packing superposed on the first named layer, and filling the central opening in the first named layer, an upper layer

of dense impervious packing superposed on the intermediate layer and filling the space between the latter and the upper cover, and means for movably supporting the closure within the silo casing, said last named means including a hoisting cable, a vertical tie member projecting through the center of the closure and attached to both the upper cover and the lower cover, and a plurality of spaced apart inclined tie members attached at their upper ends to the first named tie member and arranged to extend through the closure adjacent to its outer edge.

JULIUS MATTSON.
